(57) **CLAIM**

The ornamental design for a protective case for smartwatch, as shown and described.

DESCRIPTION

FIG. 1 is a perspective view of a first embodiment of a protective case for smartwatch, showing my new design; FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof;

FIG. 10 is a perspective view of a second embodiment of a protective case for smartwatch;

FIG. 11 is another perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof; and,

FIG. 18 is an enlarged view of portion of FIG. 10 thereof.

The broken lines shown in the drawings illustrate portions of the protective case for smartwatch that form no part of the claimed design.
